UNITED STATES PATENT OFFICE.

SYDNEY GEORGE STARLING, OF FOREST GATE, AND ARTHUR JOSEPH HUGHES, OF LONDON, ENGLAND, ASSIGNEES TO HENRY HUGHES AND SON LTD., OF LONDON, ENGLAND, A CORPORATION OF ENGLAND.

MAGNETIC COMPASS.

1,307,935.

Specification of Letters Patent. Patented June 24, 1919.

Application filed January 25, 1917. Serial No. 144,521.

To all whom it may concern:

Be it known that we, SYDNEY GEORGE STARLING, of 61 Windsor road, Forest Gate, in the county of Essex, England, and ARTHUR JOSEPH HUGHES, of 59 Fenchurch street, in the city and county of London, England, both subjects of the King of Great Britain, have invented a new and useful Improvement in and Relating to Magnetic 5 Compasses, of which the following is a specification.

This invention relates to magnetic compasses more particularly for use on aircraft and marine vessels, and has for its object to 15 suppress or to correct the errors due to the tilting of the compass card and its pivot by reason of centrifugal action caused by a rapid lateral turning movement. Errors arise by reason of the action of the vertical 20 and horizontal components of the earth's magnetic field; the error due to the former component being a semi-circular one and to the latter component a quadrantal one. Any semi-circular error is one which changes 25 twice in every complete revolution. That is, it has the same sign for 180° rotation and the opposite sign for the next 180° rotation. This is to distinguish it from a quadrantal error which changes sign every 90° of rotation. 30 Semi-circular error in a ship is due to permanent magnetization and also to vertically disposed soft iron. In an aeroplane it is chiefly due to the vertical component of the earth's magnetic field. The error due 35 to the vertical component is the more important. These errors are rectified or minimized by the present invention.

According to this invention the semi-circular error is corrected by producing a magnetic field which is vertical when the compass card is in the normal or rest position, said field being produced by means of vertically disposed magnets. In order to obtain a component of the magnetic field in the 45 plane of the card in a direction opposite to the component of the earth's vertical field in that plane when the compass card is tilted, means are provided for tilting the magnets in the same or the opposite direction to the 50 tilting of the compass card. A similar result may be obtained by raising one magnet and depressing the other.

For correcting quadrantal error provision is made for varying the distance of soft iron

masses from the compass bowl as the tilt 55 changes in turning.

The accompanying drawings are illustrative of my invention—

Figure 1 being a front view and Fig. 2 a plan view of one mode of correcting the 60 semi-circular error according to this invention.

Figs. 3 and 4 are respectively a front view and an inverted plan view of a modification.

Figs. 5 and 6 illustrate the means for correcting the quadrantal error according to 65 this invention.

In carrying out the invention and to correct the semi-circular error, the magnets 1, 1, are mounted vertically on a frame or holder 70 2 capable of rotating about an axis parallel to the fore and aft line of the aeroplane or other craft and passing through the center of the compass card mounted in the compass *a*, as illustrated in Figs. 1 and 2. The frame or holder comprises a ring *2^a* which embraces the front portion of the compass case *a* and is supported upon the latter by means of studs *2^b*, which, however, do not enter the compass case but are free to move 80 around the latter. Extending laterally from the ring *2^a* are the arms 2 which support the magnets 1. The frame and magnets may be rotated by means such as shown in Fig. 3 and comprising wires or cords 3, *3^a* passing 85 over pulleys 4, 5, the cord *3^a* being connected with the steering gear, or being operated by a stabilizer or by hand. The cord 3 is connected to the magnets 1 supported by the coil springs 1^b, both springs and magnets 90 being mounted in the casings 1^a. The magnets may have their N poles upward, in which case the attachments of the cords should be so arranged that the tilt of the magnets is in the same direction as the tilt 95 of the aeroplane. On the other hand, if the N poles of the magnets are downward, the attachment of the cords should be so arranged that the magnets rotate in the opposite direction to the tilt of the machine. In either case, the field due to the magnets is adjusted by altering the distance of the magnets or otherwise, until its strength at the compass card is as nearly as possible 100 equal to the vertical component of the earth's magnetic field, thus correcting the semi-circular error. The points of attachment of the cord to the steering gear or to the stabi-

105

lizer are found by trial and are so disposed as to cause the magnets to tilt with respect to the aeroplane to an extent which is approximately equal to the inclination of the aeroplane to the horizontal. The magnets then introduce a component of magnetic field in the plane of the compass card, equal and opposite to that of the resolved part of the earth's magnetic field in the plane of the card which latter produces the disturbance.

We employ magnets and produce the correcting field by raising one magnet and lowering the other. This could be accomplished by connecting the magnets 1, 1, together by means of the cord 3 which is passed over guide pulleys 4^a at the ends of the magnet casing 1^a and then over the pulley 4 as shown in Fig. 3. The magnets 1, 1, are supported upon helical springs 1^b so that when the pulley 4 is rotated the cord 3 pulls down one magnet and releases the other which rises under the influence of its spring. In this case the magnets are not rotated above the compass case but are moved vertically in opposite directions.

To correct both the quadrantal error due to the earth's horizontal component and the semi-circular error, soft iron is employed in conjunction with the magnets shown in Figs. 1 and 2 or Figs. 3 and 4. To enable the intensity of the field to be varied as the tilt changes, a pair of soft iron bars 6, 6, may be employed, as shown in Figs. 5 and 6, and be placed under or over the compass bowl *a*. These bars are carried by arms which are hinged together at one end and are attached to the steering gear by means of a cord in such a manner that the ends of the arms carrying the soft iron bars 6 are raised as the tilt increases.

According to the construction illustrated in Figs. 5 and 6, the soft iron correctors 6, 6, are mounted upon arms 7, 7, which are pivot-

ally mounted upon a vertical standard 8. 45 The ends of the arms 7, 7, are connected by means of links 9, 9^a, to a pin 10 mounted in a rod 10^a and working in slots 11 formed in the standard 8. The rod 10^a is connected by the part 12 with the operating device not 50 shown, and as the latter is operated the links 9 are drawn together to close the correctors 6, 6, toward the compass bowl. Springs 13 draw the arms 7 and the links 9^a together to 55 separate the correctors from the compass bowl.

What we claim as our invention and desire to secure by Letters Patent, is:—

1. The herein described mode of correcting semi-circular errors in a magnetic compass due to lateral turning movements, which consists in producing a magnetic field, the component of which in the plane of the card is in a direction opposite to the component of the earth's vertical field in that plane, substantially as described. 60

2. For correcting errors in a magnetic compass on an aeroplane, due to lateral turning movements, the combination with a compass, of a frame projecting on opposite sides of 70 said compass, vertical magnets mounted upon said frame on opposite sides of the compass, with means for moving said magnets controlled incident to the operation of the aeroplane, substantially as described. 75

3. For correcting quadrantal errors in a magnetic compass on an aeroplane, due to lateral turning movements, a pair of soft iron correctors and means controlled incident to the operation of the aeroplane, whereby 80 the correctors are drawn toward or away from the compass bowl, with change in the control of the aeroplane, thereby varying the intensity of the field, substantially as described.

SYDNEY GEORGE STARLING.
ARTHUR JOSEPH HUGHES.
